UNITED STATES PATENT OFFICE.

WILLIAM H. KING, OF CLINTON, MASSACHUSETTS, ASSIGNOR TO CROMPTON & KNOWLES LOOM WORKS, OF WORCESTER, MASSACHUSETTS, A CORPORATION OF MASSACHUSETTS.

LOCK FOR LOOM WEFT DETECTORS.

Application filed March 11, 1927. Serial No. 174,578.

This invention relates to weft detectors for looms, and it is the principal object of the invention to provide a lock to prevent indication of weft exhaustion should the shuttle be misplaced.

In weft detectors of the type set forth in patent to Ryon No. 972,722 there are provided two detectors on a slide, one of the detectors having a penetrating point which 10 is usually wedge-shaped and the other detector being pivoted to the slide and movable at weft exhaustion away from the wedge detector. A regularly moving actuator is attached to the magazine and is controlled as 15 to its operation by a pin, the position of which is determined by the swinging detector. If the detector moves forwardly without angular movement the pin is moved out of the path of the actuator but if the detector swings on its pivot while the wedge detector is in engagement with the bobbin the pin is left in the path of the actuator to 20 initiate replenishment.

When a shuttle is misplaced to such an extent that the front wall thereof engages the wedge detector the slide is moved forwardly a sufficient distance to move the pin from under the actuator lever even though the swinging detector moves angularly with 25 respect to the slide, but I find that when the shuttle is in certain misplaced positions the swinging detector will move but the slide will not be advanced sufficiently to carry the pin clear of the path of the actuator and as a 30 result a premature indication of weft exhaustion is given. This action usually takes place when the shuttle is only slightly misplaced and that portion of the shuttle at the end of the slot adjacent the wedge detector 35 engages the latter at the forward end thereof so that both detectors will be almost in contact with the bobbin when the slide is moved forwardly by the misplaced shuttle. It is an important object of my present invention 40 to extend the connector for the swinging detector so as to be engaged by a misplaced shuttle to positively withdraw the pin from under the actuator and it is a more specific object of the invention to accomplish this 45 result without lost motion between the shuttle engaging member and the pin controlling connector.

With these and other objects which will appear as the description proceeds, my

invention relates to the arrangements and 55 combinations of parts hereinafter set forth, and more particularly pointed out in the claims.

In the accompanying drawings, wherein 60 a convenient embodiment of my invention is shown:

Fig 1 is a top plan view of the detector mechanism embodying my invention, portions being removed to show the interior of 65 the slide,

Fig. 2 is an end elevation of the structure shown in Fig. 1, parts being removed for the 70 sake of clearness,

Fig. 3 is a view similar to a portion of Fig. 1 but showing the detector giving a normal indication,

Fig. 4 is a view similar to Fig. 3 but showing parts held against indication by the presence of sufficient weft, and

Fig. 5 is a detailed vertical section on line 75 5—5 of Fig. 1.

Referring to the drawings, a stand 10 which, may be secured to the loom in any approved manner, has an upstanding arm 11 provided with a transverse slot 12 which receives an actuator lever 13 which as set forth in Patent No. 1,030,748, receives a downward movement on each detecting beat of the loom. A controller pin 14 normally lies under the actuator lever 13 and is pivotally connected at the forward end thereof to an arm 15 secured to a rocking shaft 16 mounted in spaced bearings 17 formed on the stand 10. A collar 18 adjustably secured to the shaft 16 receives one end of a torsion 80 spring 19, the other end of which extends into one of the bearings as at 20. The effect of spring 19 is to hold the controller pin in the position shown in Fig. 1 under the actuator lever. The shaft 16 has secured thereto 85 another upstanding arm 21 by means of which the controller pin 14 may be moved.

The detector proper comprises a slide 30 which moves in a bed 31 connected to the stand 10 by means of stud 32 and limited in downward movement by screw 33. A cap 34 secured to the bed limits upward movement of the slide and has extending therethrough an adjusting bolt 35 which passes through a clip 36 secured to the upper face 100 of the slide. A compression spring 37 surrounds the bolt 35 and lies between the forward portion of the cap and the clip 36,

serving normally to hold the slide yieldingly in rearward position.

An eccentric screw 38 is secured to the slide and affords an adjustable pivotal 5 mounting for swinging detector 39 the rear end of which may be roughened as indicated at 40. Said detector 39 has a short arm 41 by means of which it may be moved pivotally about the eccentric screw. A wedge 10 detector 42 is secured to the slide 30 and normally projects slightly beyond the roughened surface 40 so as to penetrate a sufficient supply of weft to permit said roughened surface to be engaged by the weft in the bobbin. 15 The matter thus far described may be substantially the same as set forth in the aforesaid patents, the detector 39 being similar also to the corresponding part set forth in patent to Ryon No. 1,352,536.

20 As previously stated my invention relates to means for locking the detector 39 to prevent such angular movement thereof as accompanies indication of weft exhaustion when the shuttle is slightly misplaced. The 25 shuttle S will ordinarily have a slot 50 in its front wall of sufficient length to permit entry of the detectors 39 and 42, but it occasionally happens that the shuttle will be slightly misplaced so that the portion of the wall indicated at 51 will be positioned to engage a 30 portion of the ordinary wedge detector and permit swinging of member 39 to initiate replenishment. In carrying my improvements into effect I provide a single rod 60 formed substantially as shown in Fig. 1 and having the forward portion thereof bent to extend parallel to the shaft 16 so as to be engaged by the upper portion of arm 21. A screw 62 in said rod is positioned to engage the forward portion of the bed 31. Said rod has engagement with the detector 39, the particular form shown herein comprising a piece of sheet steel bent on itself as indicated at 63 and secured to said rod so 35 that the spaced parallel free ends 64 thereof will define a socket for the ball end of arm 41 of the swinging detector. I project the rod 60 rearwardly as shown at 65 and form the same preferably with a blunt end which projects to one side of the wedge detector 42 and terminates a short distance in front of the weft penetrating end of said wedge detector.

40 In order to restrain undue lateral movement of the rod 60 in the slide 30, I rivet a lug 70 to the slide, said lug projecting laterally from the slide to be engaged by some portion of the transfer mechanism (not shown) at the time of transfer to withdraw the detector from the path of the incoming bobbin. The inner end 71 of said lug engages an offset portion 72 of the rod 60 said offset being free to slide along the lug but being restrained against such movement toward the controller pin 14 as would cramp

the rod 60 or permit screw 62 to come in engagement with a portion of the slide.

Under normal conditions the shuttle will be properly placed and both the wedge and swinging detectors will have contact with the bobbin, both detectors moving forwardly without movement relatively to the slide when sufficient weft is present to rock shaft 16 and therefore withdraw controller pin 14 from the path of the actuator lever 13. 70 When insufficient weft for continued weaving is present the detector 39 will swing as indicated in Fig. 3 so that arms 21 and 15 will remain at rest and the controller pin 14 will be positioned to interrupt downward movement of actuator lever 13 and thus initiate replenishment. The end 65 of the rod 60 is so placed that when the detector 39 swings to the position shown in Fig. 3 said end will not engage the bobbin, but will lie 75 in advance of it so as not to interfere with the action of the detector.

When the shuttle is slightly misplaced as indicated in Fig. 1, the wall of the shuttle will engage the rear extension 65 of the rod 80 60 and push said rod forwardly so that the same will move the arm 21 and hence pin 14, to prevent indication. This action takes place immediately without lost motion and the force preventing the indication is conveyed directly from the shuttle forwardly to the lever 21 by a single member which is sufficiently rigid to withstand the blow. The roughened end 40 of detector 39, under these conditions, will be held tightly against 85 the wedge detector 42 and for this reason the slide will move forwardly. When the feeler is to be withdrawn at the time of transfer the lug 70 will be moved forwardly until the detector 39 assumes the position shown in Fig. 90 3, after which continued forward movement of the lug will move the rod 60 forwardly to withdraw the controller pin 14 from the path of the actuator lever 13.

95 From the foregoing it will be seen that I 100 have provided a very simple and durable lock for preventing indication of weft exhaustion when the shuttle is slightly misplaced and that said lock is formed as part of the operating mechanism which controls 105 the swinging detector 39. It will further be seen that the lock operates immediately upon engagement with the misplaced shuttle without lost motion. It will further be seen that the length of the extension 65 is such that 110 when the detector 39 swings to indicate weft exhaustion under normal conditions, said lock will still be somewhat in advance 115 of the yarn penetrating end of the wedge detector 42.

120 Having thus described my invention it will be apparent that changes and modifications may be made therein by those skilled in the art without departing from the spirit and scope of the invention, and I do not 125

wish to be limited to the details herein disclosed but what I claim is:

1. In weft detecting mechanism for a loom having a shuttle, a loom controller, a support, a slide movable on the support, an angularly movable detector pivoted to the slide; a rod carried by the slide and operatively connected to the angularly movable detector, said rod having an end extending rearwardly to be engaged by a misplaced shuttle, and a single spring to hold the controller yieldingly in operative position to effect change in the operation of the loom and also to hold the rod in rearward position with the rear end thereof in a position to engage the misplaced shuttle, forward movement of the rod by a misplaced shuttle being effective to move the controller out of loom controlling position.
2. In weft detecting mechanism for a loom having a shuttle, a loom controller, actuator to cooperate with the controller, a sliding

carrier, an angularly movable detector pivotally mounted on the carrier, a longitudinally movable member on the carrier having operative contact with the angularly movable detector member, said longitudinally movable member having the rear end thereof extended toward the shuttle and beyond the carrier to be engaged by the misplaced shuttle, means to operatively connect the longitudinally movable member and the controller so that forward movement of the longitudinally movable member by a misplaced shuttle will move the controller out of loom controlling position, and a single resilient means acting on the controller and the longitudinally movable member to hold said controller and last named member in normal position.

In testimony whereof I have hereunto affixed my signature.

WILLIAM H. KING.
